[57] CLAIM

The ornamental design for a combined flashlight and baton, as shown and described.

DESCRIPTION

FIG. 1 is a perspective view of the combined flashlight and baton.

FIG. 2 is a front view of the combined flashlight and baton. FIG. 3 is a right side view of the combined flashlight and baton. The left side view is symmetrical to the right side view of the combined flashlight and baton.

FIG. 4 is a back view of the combined flashlight and baton. FIG. 5 is a top view of the combined flashlight and baton; and,

FIG. 6 is a bottom view of the combined flashlight and baton.

The broken lines are shown for illustrative purposes only and form no part of the claimed design.
